(57) CLAIM

The ornamental design for a raft frame fitting as shown and described.

DESCRIPTION

FIG. 1 is a front perspective view of a raft frame fitting showing my new design;

FIG. 2 is a top view thereof;

FIG. 3 is a side view thereof, the opposite side being a mirror image of FIG. 3;

FIG. 4 is a front view thereof;

FIG. 5 is a rear view thereof;

FIG. 6 is a bottom view thereof;

FIG. 7 is a bottom perspective view thereof; and,

FIG. 8 is a top perspective view thereof when mounted to a raft frame.

The broken lines depicting the remainder of the raft frame fitting and raft frame form no part of the claimed design.

1 Claim, 8 Drawing Sheets
